UNITED STATES PATENT OFFICE.

HERBERT A. RIGGS, OF CHELSEA, MICHIGAN.

ATTACHMENT FOR WATCH-BARRELS.

SPECIFICATION forming part of Letters Patent No. 225,421, dated March 9, 1880.

Application filed November 3, 1879.

To all whom it may concern:

Be it known that I, HERBERT A. RIGGS, of Chelsea, in the county of Washtenaw and State of Michigan, have invented an Improvement in Watches, of which the following is a specification.

The nature of my invention relates to certain new and useful improvements in the construction of watches, by means of which the 10 breaking of the mainspring and uprooting of the winding parts of stem, case, or hinge winding watches is prevented.

The invention consists in the construction, combination, and arrangement of parts, so that 15 when the mainspring is fully wound up a careless continuation of turning the winding mechanism will not act upon the spring.

This invention is especially designed to entirely prevent the breaking of the mainspring 20 and uprooting of the winding parts, as is frequently the case when the winding of the watch is done hurriedly or carelessly.

The following is a full, clear, and exact description of my improvement.

25 Figure 1 is a plan view of the parts composing my improvement. Fig. 2 is a central section, showing the mechanism after having performed its intended action. Fig. 3 is a plan view of the watch-barrel. Fig. 4 is a detailed perspective view of my clutch.

Like letters indicate like parts in each figure.

In the accompanying drawings, which form a part of this specification, A represents a 35 watch-barrel, provided with the arbor B, mainspring C, and cap D, all of known construction. E is a two-forked slide, both forks being exactly alike, and having wedge-shaped ends a. This slide has upon its under side a pin, b, 40 which projects through the slot c into the barrel A and between the coils of the mainspring in such a manner that the pin is held between a single outer coil, the other coils of the spring all being on the side toward the barrel. 45 Between the forks of the slide and fitting

on the the squared portion d of the arbor is a small ratchet-wheel, F. Above this is placed another ratchet-wheel, G, which is simply sleeved on the round part of the arbor. This ratchet-wheel G has a grooved face, e. In this 50 groove engage the two forks f f of the maintaining-spring H, which is screwed to the barrel at g. These forks have studs or pins h on the side toward the barrel. Thus it will be seen that the two ratchet-wheels F G form a 55 clutch which, by means of the maintaining-spring H, can be thrown into or out of gear.

When the watch is being wound up the main winding-wheel is acting upon the ratchet G, which engages with the ratchet F, thereby 60 turning the arbor and coiling the mainspring. As soon as the last coil of the mainspring is coiling toward the center the pin b will be carried along, which moves the slide E, the wedge-shaped fork ends of which act upon the studs 65 h of the maintaining-spring, which at the termination of their travel have thrown the clutch out of gear, and any further winding will have no more effect on the spring. As the coils gradually recede again the slide E 70 travels back and the maintaining-spring will again perfect the clutch.

What I claim as my invention, and desire to secure by Letters Patent, is—

1. In combination with the arbor of the 75 mainspring and barrel of the watch, a ratchet on said arbor with a ratchet-wheel and maintaining-spring, substantially as described, and for the purpose set forth.

2. In combination with the barrel of the 80 mainspring, provided with a slot, as described, the slide, provided with a pin operating in said slot and the maintaining-spring, for the purpose of disengaging the ratchets upon the arbor when the watch or mainspring is fully 85 wound up.

HERBERT A. RIGGS.
